UNITED STATES PATENT OFFICE.

RALPH L. LEE, OF DAYTON, OHIO, ASSIGNOR TO DELCO-LIGHT COMPANY, OF DAYTON,
OHIO, A CORPORATION OF DELAWARE.

DOMESTIC APPLIANCE.

Application filed March 31, 1923. Serial No. 629,202.

The present invention relates to clothes wringer and has among its objects to provide a wringer unit comprising wringing apparatus and a power head which includes 5 preferably an electric motor, the unit adapted to be movably mounted on a suitable support, and removable therefrom.

Another object is to provide for the removal of certain elements as rolls, bearings, 10 and tension springs from one end of the wringer frame.

Another object of the present invention is to provide a compact wringer unit including wringing apparatus, a driving motor, and an 15 closed driving connection therebetween and in which certain of said elements are independently removable as sub-assemblies without disturbing the assembled relation of the other of said elements.

20 Other and further objects and advantages of the present invention will be apparent from the following description, reference being had to the accompanying drawings, wherein a preferred embodiment of one form 25 of the present invention is clearly shown.

In the drawings:

Fig. 1 is a sectional view of the wringer unit showing a portion of the driving mechanism, the section being taken on line 1—1 30 of Fig. 2;

Fig. 2 is a sectional view taken on line 2—2 of Fig. 1;

Fig. 3 is a fragmentary sectional view taken on line 3—3 of Fig. 1;

35 Fig. 4 is a fragmentary view showing a portion of the drainboard and its pivotal connections with the wringer frame;

Fig. 5 is a perspective view of the wringer removed from its supporting bracket and 40 driving mechanism showing how the wringer rolls are removed; and

Fig. 6 is a perspective view of the drainboard and conveyor showing the lock for maintaining the drainboard in either of its 45 positions.

Unitary structure.

The wringer unit comprises wringing apparatus and a power head which is trans- 50 portable in assembled relation and is adapted to be mounted upon a support and movable as a unit with respect to the support into various convenient operating positions.

The frame of the wringer unit includes a bracket 20 having a journal or hub 21 55 adapted to receive the portion 22^a of a supporting post 22, and an inverted U-shaped wringer frame 23 which is detachably secured to bracket 20 by studs 24 engaging tapped holes 24^a in frame 23, and by screws 24^b passing through holes 24^c in frame 23 and threaded into bracket 20.

The bracket 20 includes a portion which is integral with the hub 21 and which includes two flange members 20^a joined by a web 20^b. The edges of the flanges 20^a provide surfaces which are parallel to the axis of the hub 21 and provide mounting surfaces against which the wringer frame 23 is secured. The web 20^b provides a mounting 70 surface for receiving the power head to be described.

The wringer bracket hub 21 is provided with notches, one shown at 118 in Fig. 1, which are adapted to receive a lug 119 carried by post 22 for holding the wringer in a desired operating position. To change the position of the wringer the operator swings the unit causing one notch 118 to move away from lug 119 and another notch to be 80 received by lug 119 to yieldingly maintain the wringer unit in a new position.

Power head.

The power head 25 of the wringer unit will 85 now be described. This power head includes an electric motor 25^a provided with a brush lifting reversing switch operated by a lever 120. The switch is disclosed in the copending application of Ralph L. Lee, Serial No. 629,201, filed March 31, 1923. For the understanding of the present invention it is sufficient to state that the lever 120 is movable to cause the motor to turn in either direction or to stop the motor.

The casing of the motor includes a part 95 which is integral with a gear housing 27 which is attached to the web 20^b of the bracket 20 by screws 36. The armature shaft of the motor is provided with a worm 26 which is adapted to extend into the gear housing 27 and drive a worm gear 28 located therein. Gear housing 27 is open at one side and this opening is provided with a cover 29 held in place by screws 30. An oil 100 filler opening 31 is provided and is closed 105

by filler plug 32. Gear housing 27 is provided with bearing 33 which is adapted to receive operating shaft 34 to which the gear 28 is keyed. The bearing 33 provides a relatively long bearing surface for the shaft 34.

The shaft 34 extends through the gear housing 27 and a wall of the web 20^b of the bracket 20. The opening in the bracket 20 through which the shaft 34 extends is cylindrical and somewhat larger than the shaft and is adapted to receive a cup washer 37 which with the wall of housing 27 provides a lubricant receiving chamber 38.

During the operation of the motor some of the oil splashed within the gear housing 27 will enter the passage 39 and flow to the chamber 38 to lubricate the shaft 34. The excess lubricant flows through the passage 40 back into the gear housing; and, since the lubricant level in housing 27 is below the shaft 34, little if any lubricant in said chamber 38 will tend to flow out around the shaft 34.

It will be noted that the web 20^b and the flange member 20^a are offset in vertical plane from the axis of hub 21. The purpose of this is to extend the wringer frame 23 a substantial distance from the supporting post 22 so that the post is not in the way of the operator; also, by thus offsetting, the motor can be mounted substantially above said post. In this manner a compact unitary structure is provided in which the controller lever 120 for the motor is readily accessible to the operator whether the operator is on one side or the other of the wringer.

Wringer apparatus.

The wringer frame 23 includes inverted U-shaped side frames 50 and 51 held together by bolts 52. Frames 50 and 51 may be considered half shell portions, and each are provided with downwardly extending side walls 53 which form with the tops of the frames 50 and 51 a channel 53^a. Frames 50 and 51 are provided with inwardly extending ribs 54 which form guides for the roller shaft bearings 55 and 56. A spring strip member 57 is secured to each lower bearing 55 and is adapted to bear against the frames 50 and 51 to maintain said bearings 55 in correct position (see Fig. 3), and to prevent accidental dislocation of the bearings 55, such as might occur when the wringer unit is shipped with roller pressure released, or when the pressure is suddenly released by means of a quick release device to be described.

Pressure or wringer rolls 68 and 69 are carried by shafts 70 and 71, respectively. Shaft 70 bears downwardly upon the lower bearing 55 while the upper bearing 56 bears downwardly upon the shaft 71. Pressure between the rolls is supplied by a pressure

spring 72 located within the channel 53^a. Shaft 70 of the lower roll is connected with the operating shaft 34 of the power head by means of a universal coupling including sleeve 75 provided with notches 76. Shafts 34 and 70 each carry pins 77 which slide within the notches 76 and wire 78 is wrapped around the sleeve 75 so as to prevent the pin 77 from moving endwise. Shafts 70 and 71 are connected by gears 79 and 80 which are enclosed by the bracket 20.

The side walls 53 of the wringer frame members 50 and 51 extend downwardly to enclose the bearings 55 and 56 and the ends of the rolls and to provide an opening for the introduction of clothes. By enclosing the gearing, universal coupling, and roll ends, danger to the operator and to the clothes is substantially reduced.

It is apparent from the foregoing that the power head device and wringing device are removably mounted on opposite sides of the bracket 20; that the wringing device can be removed while still assembled without disturbing the power head device and that the disconnection of the wringing device automatically interrupts the power transmitting connection from the power head device to the wringing device. After the wringer is removed, the power head can be removed as a unit by removing bolts 36.

Means are provided in the wringing device for permitting endwise removal of rollers, shafts, bearings, and the springs, the wringing device being detached from bracket 20 by the removal of the nuts from studs 24 and by the removal of screws 24^a. Referring more in particular to Fig. 5, the inwardly extending ribs 54 which function as guide members for the bearings 55 and 56 are notched to provide enlarged openings 121 and 122 through one end of the wringer frame. The opening 121 is large enough that the spring 72 may be removed therethrough endwise. A lower opening 122 is large enough to permit the rollers 69 and 70 and bearings 55 and 56 to be removed endwise through it. After tension of spring 72 has been released, the spring 72 can be withdrawn through the opening 121. The upper wringer roll 69 and one bearing 56 are then pushed into the upper part of the wringer frame and in so doing the lower roller 70 can be raised high enough so that it can be removed through the opening 122. One lower bearing 55 can then be removed. The upper roller 69 is then lowered to adjacent the opening 122 and then removed, and a bearing 56 is removed.

The right hand end or branch of the wringer frame 23 is closed by the end walls of the frames 50 and 51 (see Fig. 6), and the ribs 54 adjacent this end are notched so that the other bearings 55 and 56 in this branch of the frame can be removed from the inside of the wringer frame. The bracket 20 pro-

vides a closure for the openings in the left end or branch of the wringer frame 23 so that both ends of the frame are enclosed in the unitary structure. The web 20^a provided in bracket 20 prevents the spring 72 moving endwise to the left as viewed in Fig. 1.

Wringer release.

The center of the top of the frame 50 and 51 is provided with an opening having a hinged cover or latch plate 82 pivoted at 83 and carries an adjusting screw 84 for the tension spring 72. The free end of the plate 82 is provided with a slightly upwardly inclined portion 85 which cooperates with the hook portion 86 of a latch lever 87. Latch lever 87 is pivoted upon frame 23 by pin 88, located substantially directly below the free end of the plate 82. In this manner upward tension of the spring 72 on the adjusting screw 84 and cover 82 tends to hold a hook portion 86 in engagement with the inclined portion 85 of the plate 82. When the lever 87 is pushed downwardly it will cause the hook 86 to move away from the inclined surface 85 so as to clear member 85 whereby plate 82 will swing about its pivot 83 to release the pressure on the spring 72. A spring 90 is coiled about pin 91 carried by 25 latch lever 86 and engages the under side 92 thereof and the top of frame 23. Spring 90 tends to return lever 87 to latching position. To return the cover plate 82 to the position shown in Fig. 1 after the quick release device 35 has been operated, the adjusting screw 84 is partly unscrewed and the cover 82 is swung to operating position. The plate 82 will engage the surface 93 of lever 86 thereby forcing it to snap into operating position 40 shown in Fig. 1.

Means are provided for preventing certain movable wringer parts from striking the frame when the quick release device has been operated. This means includes a bale 123 connected with cover plate 82 and passing 45 under spring 72. When plate 82 is released, the bale 123 limits its movement so that the head of screw 84 cannot strike the frame and thus damage or mar the frame.

Drain board.

The lower end of the wringer 23 carries a pivotally mounted drain board 58, mounted between rails or side frames 59 and 60. 55 Each rail carries a trunnion screw 61 rotatably and loosely journaled in larger holes 61^a provided in the branch portions of the wringer frame. Both trunnion screws 61 are removable endwise through the ends of 60 the frame. To remove the drain board, the right hand screw 61 (Fig. 1) is not placed in position until the drainboard is removed, then the board can be tilted with respect to the left hand hole 61^a because of the looseness of fit between the screw 61 and hole 61^a,

and then the board can be removed by side-wise movement without disassembling the wringer.

Drainboard 58 is provided with a locking device for maintaining the board in either 70 of its operating positions. This locking device comprises a sliding pin 63 carried by the frame 50 (see Fig. 6). Pin 63 has a notch 64 formed by flattening off a side of pin 63. A pin 65 inserted from the side of the frame 50 is received by the notch 64 and is adapted to cooperate with the ends of the notch to prevent the locking pin 63 from being pulled entirely out of the frame 23. Pin 63 cooperates with holes 66 and 67 in the side rail 60 80 so as to lock the drainboard in either of its tilted positions.

The wringer unit is provided with devices tending to direct water dropping from the wringing apparatus toward the drainboard 85 so as to prevent splattering the floor. To accomplish this the wringer is provided with water receiving ledges 113 extending under the ends of the lower roll 68 and over the drainboard rails 59 and 60. Each ledge is 90 provided with a drip flange 114 located above the drain board 58, the drain board 58 being cut away slightly as at 116 to provide clearance for said flange 114. Water tending to follow the shafts 70 and 71 drips off onto the ledges 113 and is directed by flanges 114 toward the drain board 58. The flanges 114 tend to divert water issuing endwise from the rolls toward the drain board. The drain board 58 is provided with drip strips 58^a 100 tending to prevent water running back under the drain board toward the wringer frame and dripping upon the floor.

Conveyor.

105

The drain board 58 provides a movable support for the movable wringer conveyor now to-be described. At opposite end edges of the board 58 rails 59 and 60 carry rollers 95 and 96 located parallel to the pressure 110 rolls 68 and 69, and adapted to support a conveyor belt 97 interposed between the wringer rolls 68 and 69 and therefore rotated by the movement of these rolls. Rollers 95 and 96 are tapered so as to be larger 115 in diameter at the center than at the end in order that, during the movement of the belt, the belt will remain in alignment with the wringer rolls.

While the form of mechanism herein 120 shown and described constitutes a preferred embodiment of one form of the invention, it is to be understood that other forms might be adopted and various changes and alterations made in the shape, size, and proportion of the elements therein without departing from the spirit and scope of the invention.

What is claimed is as follows:

1. In a wringer, the combination with a 130

supporting bracket; of rolling apparatus mounted on one side of said bracket; and a power head for driving the apparatus including a motor and reduction gearing, and 5 a gear housing supporting the motor and enclosing the gearing, said power head being mounted on the opposite side of said bracket.

2. The combination of a bracket having a journal adapted to receive a vertically disposed stationary bearing for supporting the bracket for rotation about a vertical axis, said bracket having integral with the journal and parallel with the axis of the journal two spaced mounting surfaces, a wringer secured 10 against one of the mounting surfaces, a wringer driving unit secured against the other surface and provided with a driving shaft, and coupling means between the mounting surfaces for connecting the shaft 15 and wringer.

3. The combination of a bracket having a hub adapted to receive a vertically disposed stationary bearing for supporting the bracket for rotation about a vertical axis, said 20 bracket having integral with the hub a portion of channel cross section provided by parallel flanges joined by a web portion which extends parallel to the axis of the hub, the web portion providing a mounting surface and the edges of the flanges which are 25 spaced from the web providing a mounting surface, a wringer secured against the edges of the flanges and cooperating with said 30 channel edge portions to provide a housing, and a wringer driving unit detachably secured to the mounting surface provided by the web and having a driving shaft extending 35 within said housing, and a coupling within the housing for connecting the shaft with the 40 wringer.

4. A wringer unit comprising, a supporting bracket having vertical supporting faces on opposite sides thereof; a unitary sub-assembly including a motor and housing, said 45 housing being carried on one of the supporting faces; wringing apparatus adapted to be driven by the motor and carried on the other supporting face; and transmission mechanism between said motor and apparatus and enclosed by the housing and bracket.

5. A wringer unit comprising, a supporting bracket having vertical supporting faces on opposite sides thereof; a unitary sub-assembly including a motor and housing, said housing being carried on one of the supporting faces; wringing apparatus adapted to be driven by the motor and carried on the other supporting face; and transmission 55 mechanism between said motor and apparatus including a detachable coupling, said mechanism being enclosed by the housing and bracket, and said wringing apparatus being independently removable from the bracket 60 and disconnectible at the coupling without 65

disturbing the assembled relation of the housing and the bracket.

6. The combination with a support; a wringer unit including a bracket carried by said support and adapted to rotate about a vertical axis, wringing apparatus carried on one side of the bracket, a motor carried on the other side of the bracket and transmission mechanism between the motor and apparatus extending through said bracket, said 70 bracket having an offset portion for carrying the apparatus at a substantial distance from the support and for carrying the motor substantially above the support.

7. In a wringer, the combination with a frame having an opening through one end thereof; of rolls supported within the frame; a pressure member for said rolls supported within said frame and removable through said opening in a direction substantially 80 parallel with the axis of the rolls and without removing the rolls from the frame and a supporting bracket for the frame detachably connected with the frame and providing a cover for said opening.

8. In a wringer, the combination with a frame having an opening through one end thereof; of a roll supported within the frame and endwise removable through said opening, and a supporting bracket for the frame 90 detachably connected with the frame and providing a cover for said opening.

9. In a wringer, the combination with a frame; of a pressure roll within the frame; a bearing for said roll; a rib providing a 100 guide for the bearing when the roll is in operative position, said frame having an opening in an end wall thereof and beyond the guide whereby to provide for the endwise removal of the roll from the frame and a 105 supporting bracket for the frame detachably connected with the frame and providing a cover for said opening.

10. A wringer unit comprising, a wringer frame, having an opening through one end thereof, a motor, a supporting bracket for carrying one of the aforementioned elements, rolls supported within the frame, and endwise removable through said opening, said 110 bracket being detachably connected with the frame and providing a cover for said opening.

11. In a wringer, the combination with a frame having an opening through an end thereof; of a roll supported within the frame and endwise removable through said opening; a supporting bracket detachably connected with the frame and providing a cover for said opening; a motor carried by the bracket; and driving connections between 120 said roll and motor extending through said bracket.

In testimony whereof I hereto affix my signature.

RALPH L. LEE.
